UNITED STATES PATENT OFFICE

FREDERICK SCHAFFERT, OF CARLSTADT, NEW JERSEY

PULLEY STILE FOR WINDOW FRAMES

Application filed February 6, 1932. Serial No. 591,373.

This invention relates to window frame constructions and comprehends the provision of an improved frame wherein the window or sash can be readily removed.

5 An object of this invention is to provide a window frame construction wherein the frame includes means for permitting the ready removal of the window for cleaning or other purposes without the necessity of removing one or more of the window stops mounted in the window frame.

10 Another object of this invention is to provide a window frame construction of this kind which is so constructed that the frame will not be weakened unduly through the provision of the means herein disclosed for removably mounting the window within the frame.

15 The above and various other objects and advantages of this invention will in part be described in and in part be understood from the following detailed description of the present preferred embodiment, the same being illustrated in the accompanying drawing, 20 wherein:—

Figure 1 is a sectional view partly in detail of a window frame constructed according to the preferred embodiment of this invention;

25 Figure 2 is a vertical sectional view taken on the line 2—2 of Figure 1;

Figure 3 is a sectional view taken on the line 3—3 of Figure 2.

30 Referring to the drawing wherein like characters of reference designate corresponding parts throughout the several views, the letter F designates generally a window frame construction including side frame members 10, an inner stop member 11, a parting stop 12 and an outer or blind stop 13.

35 The side frame member 10 has a passage 14 through the upper end portion thereof within which a sheave or pulley is mounted for training a weighted rope thereover so as to balance the window sash within the frame F. 40 That portion of the side frame member 10 between the inner and the parting stop members 11 and 12, respectively, and between the parting and the outer or blind stop 13 is grooved or inwardly offset, as at 15, and the length of this rabbet or offset portion is preferably sub-

stantially equal to the length of the stop members 11, 12 and 13.

45 The filler or removable plate 16 is removably mounted in this rabbeted portion 15 and when so mounted, the outer surface of the 55 filler plate 16 is substantially coplanar with the adjacent face of the side frame member 10 so that the window sash can readily slide up or down within the groove formed between two of the stop members. This filler 60 or bar 16 is provided with an aperture 17 therethrough and a securing member in the form of a staple, nail or the like 18, is mounted in the sill portion 19 of the window frame and engages the lower end of the filler 16 so 65 that the filler will not readily come out of the rabbeted portion 15.

70 Preferably, the length of the filler 16 is slightly greater than the height of the window sash so that the upper end of the filler 16 70 is relatively free, but the filler is shorter than the length of the rabbeted portion 15. In order to provide means whereby the filler 16 may be readily removed from the rabbet 15, I have provided a tapering upper end portion 75 20 on the filler 16 so that when the filler 16 has been moved upwardly, the lower end thereof will pass the top of the securing member 18 and the lower end portion may then be swung outwardly of the rabbet 15 with the upper 80 end thereof disposed between the edge of the window sash and the side frame member 10.

85 In the use of this device, the window sash is slidably disposed between pairs of the stop members 11, 12 and 13, and the filler 16 will be disposed in the rabbeted portion 15 and held therein by contact with a portion of the window sash and through the medium of the securing member 18. When it is desired to 90 clean the window, particularly on the outside, the filler 16 can be removed by moving it upwardly to a point above the securing member 18 and then inwardly. The window sash can then be lowered to the point where the upper end thereof will be coplanar or below the upper 95 end of the rabbeted portion 15, whereupon the window sash can be moved laterally so as to carry the opposite edge thereof outward of the space between adjacent stops carried by the side frame member 10. The win- 100

dow sash can then be swung reversely, being supported by the conventional pulley cord carried on each side thereof.

It will be obvious from the foregoing that a relatively simple window frame construction has been designed wherein the sides of the window frame will not be unduly weakened through the provision of means for moving the window frame into released position and that it will not be necessary to remove any of the stop members carried by the window frame to hold the sash in sliding position within the frame.

It will also be noted that this window frame construction can readily be made out of either wood or metal, and that a window frame constructed according to the preferred embodiment of this invention may have the usual removable stop members formed integrally with the sides, thereby reducing the cost of the window frame construction.

It is, of course, understood that various changes and modifications may be made in the details of construction and design of the above specifically described embodiment of this invention without departing from the spirit thereof, such changes and modifications being restricted only by the scope of the following claims.

30 What is claimed is:—

1. In a window frame construction, a pair of side frame members, a plurality of parallel vertically extending stop members carried by the side members, each of said side members having an inwardly offset rabbeted portion disposed between pairs of stops, said rabbeted portion terminating at one end intermediate the ends of the side member and extending to the extremity of the opposite end of the side member, an elongated member seated in the rabbeted portion and having the inner face thereof substantially coplanar with the adjacent face of the side member, said elongated member being of a thickness substantially equal to the depth of the stop members, and means engaging the window sill for removably mounting the elongated member in the rabbeted portion, said elongated member having the inner surface thereof adjacent the upper end inclined upwardly and outwardly to provide a reduced upper end to permit removal thereof.

2. In a window frame construction, a pair of side members, a plurality of parallel vertically extending window sash stops carried by the side members, said side members having a rabbeted portion of a length substantially greater than the height of the window sash, a narrow strip removably mounted in said rabbeted portion and having a length less than the length of the rabbeted portion, and means for removably mounting the strip in the rabbeted portion, said means including a staple of a length when in position in 60 the lower horizontal portion of the frame less

than the distance between the upper end of the strip and the adjacent end of the rabbeted portion to permit removal of the strip by upward sliding movement followed by outward movement.

70 In testimony whereof I hereunto affix my signature.

FREDERICK SCHAFFERT.
